CLAIM

The ornamental design for a display, as shown and described.

DESCRIPTION

FIG. 1 is a perspective view of a display showing the inventive design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a second perspective view thereof; and,

FIG. 9 is an enlarged view of portion '9' in FIG. 8.

The evenly-dashed broken lines illustrate portions of the display that form no part of the claimed design. The dash-dot broken lines in FIGS. 8-9 represent the extents of the enlarged detail view and form no part thereof.
